H. A. DOUGLAS,
CIRCUIT CONNECTOR.
APPLICATION FILED APR. 17, 1916.

1,220,141.

Patented Mar. 20, 1917.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

CIRCUIT-CONNECTOR.

1,220,141.

Specification of Letters Patent. Patented Mar. 20, 1917.

Application filed April 17, 1916. Serial No. 91,547.

To all whom it may concern:

Be it known that I, HARRY A. DOUGLAS, citizen of the United States, residing at Bronson, in the county of Branch and State 5 of Michigan, have invented a certain new and useful Improvement in Circuit-Connectors, of which the following is a full, clear, concise, and exact description, reference being had to the accompanying drawings, 10 forming a part of this specification.

My invention relates to circuit connectors, a connector of my invention including a shell, a circuit continuing member coupled with the shell and carrying two contacts, 15 two additional contacts within the shell each for engaging one of the aforesaid contacts, a spring pressing each additional contact into engagement with its complemental contact on said circuit continuing member, said 20 circuit continuing member and the shell having interengaging coupling formations serving to position this circuit continuing member in inner and outer positions respectively to make and break circuit, one of said 25 additional contacts having means for stopping its movement before said circuit continuing member reaches its outer position, while the spring pressing the other additional contact maintains this other additional 30 contact in engagement with this circuit continuing member in its outer position, and a carrier for said additional contacts which is movable longitudinally within the shell. In the most complete embodiment of 35 my invention I have employed a circuit continuing member at each end of the shell and have provided two pairs of contacts within the shell, one contact of each pair engaging one circuit continuing member and the other 40 contact of each pair engaging the other circuit continuing member and a spring interposed between the contacts of each pair for maintaining them in engagement with the circuit continuing members, one only of the 45 two contacts associated with the outer circuit continuing member that is adjustable longitudinally of the shell having means for stopping its movement after this circuit continuing member has left its inner position. 50

I will explain my invention more fully by reference to the accompanying drawing showing the preferred embodiment thereof and in which Figure 1 is a view in elevation, 55 partially in section, of a structure inclusive

of my invention; Fig. 2 illustrates certain of the parts shown in Fig. 1 in another adjustment; Fig. 3 is a view on line 3 3 of Fig. 4; and Fig. 4 is a view on line 4 4 of Fig. 1.

Like parts are indicated by similar characters of reference throughout the different figures.

The structure illustrated is inclusive of a shell 1, preferably metallic, inclosing a contact carrier 2 of insulating material which is movable longitudinally of the shell, being limited in such movement by the inturned ears 3 and which carrier 2 is guided in its movement by the ribs 3¹ that enters slots in 70 the sides of the carrier.

The connector illustrated is a so-called double pole connector to which the invention is not to be limited. The contact carrier is shown as carrying two pairs of contacts, 4, 5, 75 6, 7. The contacts 4, 5 of one pair are preferably in telescoping engagement as are the contacts 6, 7 of the other pair and all these contacts, except contact 6, are movable, with relation to the carrier, in the bores that are 80 provided therethrough and which extend longitudinally of the shell 1, and all of the contacts 4, 5, 6 and 7 are movable with respect to the shell irrespective of the interrelation of these contacts and the carrier 2.

The contact 6 is desirably substantially fixed with respect to the contact carrier 2. One of the circuit continuing portions which is adapted to be included in circuit by means of the connector is shown in the form of a 85 lamp 8 whose filament 9 is connected with the lamp terminals 10 and 11 that are provided upon the end of the lamp base 12 (constituting a circuit continuing member) this lamp base constituting a contact carrier 90 for the lamp terminals. The end of the shell 1 that is to receive the base of the lamp is provided with bayonet slots 13 (constituting coupling formations) adapted to receive bayonet pins 14 (also constituting coupling 95 formations) projecting from the lamp base. The other end of the shell 1 is adapted to receive a plug 15 (also constituting a circuit-continuing member) and which is a carrier for contacts 16 and 17 which are connected with or adapted for connection with a suitable source of current. The end of the shell that receives the plug 15 is provided with bayonet slots 18 each having two seats 19 and 20 (constituting coupling forma-

110

tions) that are separated longitudinally of the shell whereby the bayonet pins 21 (also constituting coupling formations) may be interengaged with the shell at 5 different places longitudinally thereof for the purpose of holding the plug 15 in assembly with the shell while the plug is either in an inner or outer position while assembled with the shell, the arrangement being such 10 that when the plug is in its innermost position it will be included in circuit with the lamp and when it is in its outermost position it will be excluded from such circuit.

While I have shown circuit continuing 15 portions in the form of a lamp 8 and a connecting plug 15, I do not wish to be limited to the nature of the circuit continuing portions that may be connected by means of my connector.

20 The contacts 5 and 6 are in the form of spring barrels each housing a spring 22, one end of such spring engaging one end of its inclosing barrel while the other end of such spring engages the plunger contact 4 or 7 25 that is telescopically received within the barrel. Thus each spring 22 is interposed between the telescopically engaging contacts of a pair to maintain these contacts in their outermost positions or the positions 30 permitted therefor by the contact carriers. The extent to which the plunger contacts may be outwardly thrust by the springs is limited by the shoulders 23 whereby the contacts of each pair are maintained in assembly when the plunger contacts 4, 7 are 35 out of engagement respectively with the contacts 10 and 17, a condition which arises when the contact carriers supporting these contacts 10 and 17 are withdrawn from the 40 shell 1. The extent to which the current conveying contacting spring barrel 5 may be moved with reference to the contact carrier 2 is limited by shoulders, flanges or enlargements 24, 25. The shoulders 24¹, 25¹ 45 upon the contact 6 are both in firm engagement with the contact carrier 2 and move with this contact carrier, the movement of the contact 6 being limited by the engagement of the carrier 2 with the ears 3. The 50 arrangement of the contact carrier 2 is such that the contact 7 will be constantly in engagement with the contact 17 when the plug 15 is in either of its positions. The distance 55 between the flanges 24 and 25 of the contact 5 and between the carrier 2 and the lower ears 3 is such, however, that the spring within the contact 5 can cause this contact to follow the contact 16 only for a short distance when this contact is being put into its outer 60 position. That is the contact 5 may be firmly pressed by the spring inclosed by this contact against the contact 16 when the plug 15 is in its innermost position (with the bayonet pins 21 in the seats 19) but cannot 65 maintain such engagement when the bayo-

net pins are in the seats 20. Thus when the plug 15 is in its innermost position the lamp is included in circuit and when this plug is in its outermost position the circuit of the lamp is broken at the contacts 5 and 16. 70 Both springs 22, however, continue the pressing engagement between the contacts 4 and 10 and contacts 6 and 11 whether the plug 15 is in its inner or outer position so that these springs both serve to maintain the bayonet pins 14 in the bayonet slots 13 as indicated. 75 If the plug 15 is totally removed from the shell 1 then the spring 22 within the spring barrel 5 will continue the pressing engagement between the contacts 4 and 10 whereby the lamp 8 is still maintained in proper assembly with the shell 1. If the lamp is removed from the shell then the spring 22 within the spring barrel 6 will maintain pressing engagement between the contacts 7 and 17 when the plug 15 is in either its inner or outer position while within the shell, the floating carrier 2 then resting against the upper ears 3, this spring then serving to maintain the plug and shell in 90 assembly.

It will be observed that the telescopically related contacts of each pair are supplemented only by a spring that tends to spread them apart whereby the formation of compressible contacts employed in devices of this class is much simplified. By this telescopic arrangement of contacts there is only one place in each set of contacts where the contacts are in changing relation or in sliding engagement with each other whereby the resistance in the portion of the lamp circuit extraneous to the lamp is maintained at a minimum while at the same time the contacts of each set or pair are adapted to perform the mechanical functions apportioned to it. Moreover, the contacts 10 and 11 upon the carrier 12 may be more closely approached to the contacts 16 and 17 upon the carrier 15 inasmuch as the space occupied by the coupling contacts intervening between the contact carriers 12 and 15 is much reduced by means of my invention. In my device, therefore, the aggregate length of the entire structure is materially shortened. 105 While I have shown two pairs of such contacts and have given to one the mechanical function of holding circuit continuing members in mechanical assembly while these members are electrically separate, I do not 110 wish to be limited to a construction in which the contact members of a pair of contacts are adapted to the function of conducting current as well as to the performance of the stated mechanical function, this double 115 function obtaining when the structure is embodied in a double pole arrangement to which the invention is not to be limited.

While I have shown an arrangement in 120 which the plug 15 is adapted to be placed 125 130

in inner and outer positions for the purpose of including the lamp in and excluding it from circuit, I do not wish to be limited to this arrangement, it being apparent that mechanical separation between the contact 5 and the contact carrier 15 is not essential to the realization of all of the advantages of my invention.

Though the contacts of each pair 4, 5, 6, 10 7 are shown in sliding engagement, I do not wish to be limited to this arrangement since the interposed spring 22 or other means could be relied upon for bringing the contacts between which such spring is interposed into electrical connection without relying upon the engagement between such contacts.

While I have herein shown and particularly described the preferred embodiment of 20 my invention I do not wish to be limited to the precise details of construction shown as changes may readily be made without departing from the spirit of my invention, but having thus described my invention I 25 claim as new and desire to secure by Letters Patent the following:—

1. A connector including a shell; a circuit continuing member within each end of the shell; two pairs of contacts within the shell one contact of each pair engaging one circuit continuing member and the other contact of each pair engaging the other circuit continuing member; a spring interposed between the contacts of each pair for maintaining them in engagement with the circuit continuing members, one of said circuit continuing members and the shell having interengaging coupling formations serving to 30 position this circuit continuing member in inner and outer positions respectively to make and break circuit, a contact, of one pair, pressed toward this circuit continuing

member having means for stopping its movement after this circuit continuing member has left its inner position and before it reaches its outer position, while a contact of the other pair is maintained in engagement with this circuit continuing member by its spring in both positions of this circuit continuing member; and a third circuit continuing member within the shell and movable longitudinally thereof and to which third circuit continuing member one of the contacts of each of the aforesaid pairs is substantially fixed. 45 50 55

2. A connector including a shell; a circuit continuing member coupled with the shell and carrying two contacts; two additional contacts within the shell each for engaging one of the aforesaid contacts; a spring pressing each additional contact into engagement with its complemental contact on said circuit continuing member, said circuit continuing member and the shell having interengaging coupling formations serving to position this circuit continuing member in inner and outer positions respectively to make and break circuit, one of said additional contacts having means for stopping its movement before said circuit continuing member reaches its outer position, while the spring pressing the other additional contact maintains this other additional contact in engagement with this circuit continuing member in its outer position; and a carrier 60 65 70 75 for said additional contacts which is movable longitudinally within the shell.

In witness whereof, I hereunto subscribe my name this 7th day of April, A. D. 1916.

HARRY A. DOUGLAS.
